(57) **CLAIM**

The ornamental design for a scooter, as shown and described.

DESCRIPTION

FIG. 1 is a perspective view of a scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the scooter where the scooter is in a folded state;

FIG. 10 is an enlarged view of the handlebars, taken from the top of FIG. 1;

FIG. 11 is an enlarged view of the front wheel and deck, taken from the left of FIG. 1;

FIG. 12 is an enlarged view of the rear wheel area, taken from the right of FIG. 1;

FIG. 13 is an enlarged view of the handlebars, taken from the top of FIG. 2;

FIG. 14 is an enlarged view of the handlebars, taken from the top of FIG. 3; and,

FIG. 15 is an enlarged view of the handlebars and front wheel, taken from the bottom of FIG. 7.

The broken lines in the drawings depict portions of the scooter that form no part of the claimed design. The dash-dot broken lines in FIGS. 10-15 represent the boundaries of the enlarged partial views. None of the broken lines form a part of the claimed design.
